UNITED STATES PATENT OFFICE

CARL GRUNWALD, OF BREDENEY, GERMANY.

FUEL-INJECTING DEVICE FOR INTERNAL-COMBUSTION ENGINES.

1,310,565.

Specification of Letters Patent. Patented July 22, 1919.

Application filed July 24, 1912, Serial No. 711,377. Renewal December 4, 1918. Serial No. 265,312.

To all whom it may concern:

Be it known that I, CARL GRUNWALD, a citizen of the German Empire, residing at Bredeney, Germany, have invented certain new and useful Improvements in Fuel-Injecting Devices for Internal-Combustion Engines, of which the following is a specification.

Internal combustion engines with fuel injection using slowly igniting fuel such as tar oil, have the disadvantage, that the ignition will cease when the engine runs with a light load. The reason for this is that with a light load, only a small quantity of fuel is injected, and that in consequence the fuel will be completely blown away from the atomizer, or more correctly, from the circular space above the needle seat and that when the fuel valve is next opened, cold compressed air runs into the working cylinder and prevents the subsequent ignition of the fuel. It has on the other hand been found that the ignition occurs with certainty, when care is taken that at least a very small quantity of fuel is present in the space directly above the needle seat of the fuel valve when the latter is opened.

In order to attain this, and to avoid the disadvantage mentioned above, the circular space located above the needle seat will, in accordance with this invention, be brought momentarily in connection with the inside of the working cylinder before the raising of the needle which serves to introduce the fuel.

One embodiment of the invention is illustrated in the drawing, and:

Figure 1 shows a longitudinal vertical section through a fuel valve and a part of the working cylinder;

Fig. 2 a top plan view of a particular kind of gearing for the fuel valve illustrated in Fig. 1;

Fig. 3 a second embodiment corresponding to Fig. 1 of a fuel injecting device and

Fig. 4 the cam gear belonging to Fig. 3, as seen from the left.

The embodiment of the invention shown in Figs. 1 and 2 will first be described. A valve cage A inserted in the cover M of the working cylinder incloses the fuel needle B which is governed by the cam disk N by means of a lever P; and C are atomizing plates, and D the atomizing cone. The ports E and F serve to provide the fuel and the atomizing compressed air.

Beside the usual fuel cam tooth n^1 on the

cam disk N is, according to this invention, another small cam tooth n^2 provided and placed in front of the fuel cam tooth n^1 counted in a direction of rotation indicated by the arrow. This auxiliary cam tooth causes a momentary raising and closing of the fuel needle B preceding the opening of the fuel valve. As now the pressure in the working cylinder is less than the pressure in the fuel valve, a diminishing of pressure will occur in the circular space G by means of this momentary raising of the fuel needle B and a consequent advancement of fuel supplied by the pump will take place in the nozzle, so that at the second opening of the fuel valve caused by the cam tooth n^1 , no cold compressed air but fuel will be injected in the working cylinder, so that a more certain ignition is assured.

As the danger of the ceasing of the ignition only exists when the engine runs under a small load, the above described control of the fuel needle may therefore be arranged in such a manner, that the auxiliary cam tooth n^2 only comes into action when the load is diminished below a certain limit (to about half load); and that otherwise the duration of the advanced opening or the width of the advanced opening of the fuel needle will be increased with the diminishing load. Such an arrangement of the two cam teeth n^1 and n^2 on the cam disk N is shown in Fig. 2. As will be seen in this figure, the main cam tooth n^1 for the fuel supply is about twice as wide as the auxiliary cam tooth n^2 . The auxiliary cam tooth n^2 has furthermore two running surfaces of different height which are connected with each other and with the circumferential surface of the cam through inclined surfaces. The cam disk N is in usual manner axially displaceable on the gear shaft R by means of groove and key and can be adjusted in three different positions (I II III) by means of the adjusting lever S. When the engine is under full load, the lever S occupies the position I. The cam disk will then take the position relative to the lever P shown in Fig. 2 so that the gear roller p^1 will cooperate with the fuel cam tooth n^1 . Should the load of the machine now be diminished to about half load, the adjusting lever will be transferred to the middle position II. As a consequence the lower part of the auxiliary cam tooth n^2 will then arrive in the path of the gear roller. An advanced

opening of the fuel valve will then take place before the main injecting of the fuel. Lastly when the engine runs empty the adjusting lever I would be brought into the 5 position III whereby the high part of the auxiliary cam tooth n^2 will come into action and a greater advanced opening of the fuel valve will be the consequence.

The position of the auxiliary cam tooth n^2 10 on the cam disk N has to be found by experiment.

The difference between the embodiment 15 represented in Figs. 3 and 4, from the described embodiment consists particularly therein that the connection of the circular 20 space G with the working cylinder is not made through the fuel nozzle but rather through a separately geared by-pass K. The opening of this by-pass and the closing thereof, is here actuated by means of the auxiliary needle valve L which is also operated by the cam disk N by means of a second 25 lifting lever T situated in advance of the lever P. For this purpose a second cam tooth n^2 is provided besides the normal fuel 30 cam tooth n^1 on the cam disk N, and this second cam tooth is situated in advance of the fuel cam tooth n^1 in the revolving direction indicated by the arrow. This second 35 cam tooth n^2 , in this case, is not located in the same plane as the cam tooth n^1 but instead in the plan of the gear lever T which belongs thereto (see Fig. 4). This auxiliary 40 cam tooth n^2 acts in such a manner on the needle of the auxiliary valve L that a momentary connection between the circular space G and the cylinder is established 45 through the short raising and lowering in advance of the opening of the fuel valve, and that thereby a diminishing of pressure 50 in the circular space will take place. The action of this on the fuel is the same as in the previously described embodiment.

I claim:

45 1. In a fuel injecting device for internal combustion engines, using slowly igniting fuel; the combination with a working cylinder, a fuel valve for the cylinder, and a seat for said valve, of an annular space behind said seat said space having normally closed connection with the cylinder; and means for momentarily connecting said annular space with the cylinder thereby permitting fluid to escape from said space into the cylinder in advance of the regular opening of the valve admitting fuel into the cylinder.

2. In a fuel injecting device for internal 60 combustion engines, using slowly igniting fuel; the combination with a working cylinder, a fuel valve for the cylinder, and a seat for said valve, a cam gear for actuating said valve; of an annular space behind said seat, said space having normally closed 65 connection with the cylinder; said cam gear

adapted to momentarily connect said annular space with the working cylinder thereby diminishing the pressure in said space in advance of the regular opening of the valve for admitting fuel into the cylinder.

3. In a fuel injecting device for internal combustion engines, using slowly igniting fuel; the combination with a working cylinder, a fuel valve for the cylinder, and a seat for said valve, of an annular space behind said seat, said space having normally closed connection with the cylinder; means for actuating said valve, comprising a two armed lever, a revolving shaft and a cam disk thereon having a series of projections for oscillating said lever at certain intervals, whereby said annular space will be momentarily connected with the working cylinder in advance of the opening of the valve by said means for admitting fuel into the cylinder.

4. In a fuel injecting device for internal combustion engines, using slowly igniting fuel; the combination with a working cylinder, a fuel valve for the cylinder, and a seat for said valve, of an annular space behind said seat, means for actuating said valve, comprising a two armed lever, a revolving shaft and a cam disk thereon for oscillating said lever at certain intervals, said cam disk having a wide cam tooth and a plurality of narrow cam teeth of different heights and arranged in alinement and parallel to the axis of said disk, said narrow cam teeth being so mounted on said disk, that they can actuate the valve, for connecting said space with said working cylinder, in advance of the action of said wide cam tooth to open the valve for admitting fuel into the cylinder.

5. In a fuel injecting device for internal combustion engines, using slowly igniting fuel; the combination with a working cylinder, a fuel valve for the cylinder, and a seat for said valve, of an annular space behind said seat, means for actuating said valve, comprising a two armed lever, a revolving shaft and a cam disk thereon for oscillating said lever at certain intervals; said cam disk having a wide cam tooth and a plurality of narrow cam teeth of different heights and arranged in alinement and parallel to the axis of said disk, said narrow cam teeth being so mounted on said disk, that any one of them may be brought in the path of said lever in advance of said wide cam tooth, during the rotation of said cam disk.

6. In a fuel injecting device for internal 125 combustion engines, using slowly igniting fuel; the combination with a working cylinder, a fuel valve for the cylinder, and a seat for said valve, of an annular space behind said seat, means for actuating said

valve, comprising a two armed lever, a revolving shaft and a cam disk thereon for oscillating said lever at certain intervals, said cam disk being axially displaceable on 5 said shaft and provided with a wide cam tooth and a plurality of axially aligned narrow cam teeth of different heights and means for axially displacing said cam disk whereby said narrow cam teeth may be 10 brought into the path of said lever in advance of said wide cam tooth when the en-

gine load is diminished, whereby said annular space will be momentarily connected with the working cylinder in advance of the opening of the valve by said means for admitting fuel into the cylinder. 15

In testimony whereof I have affixed my signature in presence of two witnesses.

CARL GRUNWALD.
